CLAIM

The ornamental design for a refrigerant reclamation unit, as shown and described.

DESCRIPTION

FIG. 1 is a perspective view of a refrigerant reclamation unit showing our new design;

FIG. 2 is a top plan view thereof;

FIG. 3 is a left side elevational view thereof;

FIG. 4 is a bottom plan view thereof;

FIG. 5 is a right side elevational view thereof;

FIG. 6 is a front elevational view thereof; and,

FIG. 7 is a rear elevational view thereof.

FIG.2

FIG.3

FIG.4

FIG.5

FIG.7
